AMMUNITION

Aaron L. Hitchens, North Ridge, Calif., and Emil Czapek, Woodbridge, Conn., assignors to Olin Mathieson Chemical Corporation, East Alton, Ill., a corporation of Virginia

Application December 2, 1955, Serial No. 550,570

6 Claims. (Cl. 102—42)

This invention relates generally to ammunition and more particularly to gun cartridges and to a method for making the same.

In the manufacture of shotgun cartridges, it has been the custom, heretofore, to make the case from a relatively pliant and resilient convolute wound paper tube and a metallic head which closes one end of the tube. This type of cartridge is not entirely satisfactory, however, because the region of the tubular body adjacent the metallic head and particularly substantially adjacent to the flange or extraction rim of the head sometimes expands when the cartridge is fired rendering extraction thereof from the gun chamber extremely difficult. In fact, in some instances the head becomes detached from the tubular body by the gun's extraction mechanism. In other instances, the friction between the cartridge case and the gun's chamber is so great that none of the cartridge case can be removed by the average gun's extracting mechanism. These disadvantages of such a cartridge are hazardous as well as troublesome to the shooter for it sometimes happens that a cartridge is inserted and fired in the chamber of a gun which contains the tubular body of a preceding cartridge often with serious injury to the shooter.

In view of these disadvantages of the paper shotgun cartridge having a metallic head, many attempts have been made to overcome this defective condition. It has been recognized that the expansion or bulging of the breech end of the cartridge case is due to the pressure of the gases developed by the explosion of the propellant charge and numerous expedients therefor have been proposed. Probably the most successful of these is the provision of an obturating basewad within the tubular body and adjacent the metallic head thereof, but even the best of these wads may fail to completely seal the breech portion of the cartridge against gas leakage. It has also been suggested, as for example, in U.S. Patent 1,171,313 issued to Bonham, February 8, 1916, that one end of the tubular body be folded about the end of the basewad and that the tube wall be forced into the extraction rim or flange of the metallic head by means of a metallic disk. This expedient has not been completely successful, however, as it involves a rather cumbersome manufacturing step and does not eliminate separation of the head from the tubular body when the cartridge is fired.

Numerous other shotgun cartridge cases have been proposed including cases molded from various plastic or synthetic resinous compositions or cases molded from paper pulp or papier maché but none have been found entirely satisfactory primarily because the tubular body thereof is not sufficiently pliant or elastic to function properly in a shotgun.

It is therefore an object of this invention to provide a novel gun cartridge in which the metallic head is eliminated. It is another object of this invention to provide a shotgun cartridge having the advantages of the usual paper cartridge but devoid of the disadvantages inherent with the prior construction. A further object of this in-

2

vention is to provide a method for making a novel shotgun cartridge case having a paper tubular body. A still further object is to provide an improved case for shotgun cartridges.

5 Other objects will become apparent from the following description and accompanying drawing in which:

Figure 1 illustrates, in a vertical view in section, suitable apparatus for making an embodiment of this invention, and

10 Figure 2 is a vertical sectional view of a cartridge illustrating an embodiment of this invention made in apparatus such as illustrated in Figure 1.

In accordance with this invention, generally stated, the foregoing objects as well as others are achieved by 15 providing a shotgun cartridge with a plastic head and a paper tubular body having one end thereof folded inwardly and embedded in the plastic head, thereby securely locking the tube and head together. This invention also provides a method for forming the plastic head about and 20 in locking engagement with one end of the tubular body in such a way that the head is not removed from the tubular body by the extraction mechanism of the gun. By "plastic" head or base as utilized herein and in the appended claims is meant a head formed from a resinous 25 material which can be shaped in a softened state and hardened thereafter. Either a thermoplastic or a thermosetting type resin is suitable for the purpose provided that the required period of time at the molding or casting temperature thereof is below that point at which the 30 properties of the paper tube will be deleteriously affected.

In general, in making the cartridge case of this invention, a paper tube is convolutely wound using a suitable adhesive such as casein or starch, waterproofed and sized in accordance with known processes. The basewad is positioned within the tube so that it is spaced away from the end and that portion of the tube extending from the bottom of the basewad is subsequently folded over and about the external edges of the bottom of the wad; it being preferred that the angle of the bend be less 40 than ninety degrees for the usual flat-bottomed wad illustrated, i.e. that angle which leaves the folded end spaced from the wad as shown. A shotgun cartridge head or base is molded about the inwardly extending end of the tube by submerging it in a suitable molten resinous material confined in a die of suitable configuration and 45 hardening the resinous material about the tube end.

It has been found that a shotgun cartridge having a case made in accordance with this invention is a vast improvement over the various shotgun cartridges of the prior art because the advantageous characteristics of the laminated paper tube have been retained and, in addition, the breech end of the cartridge has been improved. In contradistinction to the paper shotgun cartridge having a metallic head, the shotgun cartridge of this invention is 50 easily ejected from the gun chamber. In fact, it has been found that basewads which do not provide sufficient obturation to permit their use in the metallic headed prior art paper cartridge, as well as the better obturating wads, can be successfully utilized in a shotgun cartridge made in accordance with this invention because the breech end

55 of the plastic headed cartridge does not become permanently expanded by the gases developed by the explosion of the propellant charge. Cartridges having the breech structure provided by this invention have been successfully reloaded and again fired without malfunctioning thereof. The plastic head also assists the basewad in providing rigidity to the breech end of the cartridge and thus assists in imparting the characteristic required for proper initiation of the priming charge. It is apparent, therefore, that the cartridge provided by this invention 60 has advantageous properties in addition to the important advantage of providing a substitute for the shotgun car- 65

tridge having a metallic head when shortages of metal exist, particularly during a war era.

Referring now to the accompanying drawing for a description of one embodiment of this invention, a multi-laminar tube conveniently of sufficient length that several tubular bodies can be cut therefrom is wound about a suitable mandrel from paper coated with casein paste and is then successively dried, sized, and cut to the required length in accordance with well known practice. The tube is then impregnated with paraffin or similar wax and a basewad is first compressed and then positioned therein in accordance with known methods except the basewad is positioned with the bottom or that end thereof designated to be substantially adjacent the head of the cartridge spaced inwardly from one end of the tube. A mandrel is now inserted in the tube and the end of the tube is forced into a die having a concave cavity therein to fold that portion extending from the bottom of the basewad inwardly at an angle of less than ninety degrees. The folded over portion should be bent around the outer edge of the wad and fit snugly thereagainst.

Die 4 and two-piece casting die 9 and 11 are assembled as shown in Figure 1 and a preformed disk of a molding compound of ethyl cellulose having a melting point of about 150° C. is placed in cavity 5. The ethyl cellulose is heated to about 185 to 225° C. A laminated paper tube 1 formed as described hereinbefore is placed on mandrel 2 having handle 3 and is inserted in die 4 with the bend over end 6 of tube 1 extending beyond the bottom end of basewad 7 into the plastic material. Mandrel 2 rests on basewad 7 and pressure is exerted through mandrel 2 against basewad 7 until the assembly of tube 1 and basewad 7 is moved in the direction indicated by the arrow in Figure 1 to a position in mold cavity 5 such that at least about one-half of the basewad 7 and that portion of tube 1 thereabout is contained therein. Conical pin 8 serves to properly align tube 1 with cavity 5, to stop tube 1 at the proper level therein and to form a pocket for later insertion of the primer assembly. The pressure exerted through mandrel 2 is maintained until the plastic has cooled and solidified. To facilitate removal of the cartridge case from the die, die cavity 5 is composed of two component parts, a cylindrical cavity 23 in die block 11 for forming the base of the head including the extraction rim and a cylindrical opening 22 through die block 9 for forming part of the base and the sidewalls of the cartridge head, as shown.

After the ethyl cellulose has cooled to below its melting point and preferably to 80 or 90° C., die blocks 9 and 11 which are fastened together by pins 10 and 12 forming a friction fit in corresponding cavities in each of these parts are separated by moving die block 9 and die 4 in a direction opposite to that designated by the arrow in Figure 1. A primer assembly comprising a conventional battery cup 13, a primer cup, a priming composition and an anvil is inserted with conventional apparatus in the primer pocket in head or base 14 in the position shown in Figure 2 and the tubular body 1 is charged with propellant 15, filler wads 16 and 17 and projectiles 18. The end 19 of tube 1 is crimped over wad 20 to completely enclose the contents of the cartridge case.

Although in the foregoing, one embodiment of this invention is described in detail, this invention is not limited to such details as numerous variations can be made. Other suitably plasterized resinous materials such as, for example, melamine formaldehyde resins, urea formaldehyde resins, methyl methacrylate, ethyl methacrylate, polyamides, cellulose acetate and the like and molding compounds containing the same can be utilized for forming the cartridge head. Suitable plasticizers include dibutyl phthalate and the like. The laminated tube can be rolled with a water type adhesive such as described above or the tube can be rolled with a resinous material such as ethyl cellulose, polystyrene, synthetic rubber, such as

neoprene, and the like, dissolved in a suitable solvent or while molten. In some instances, when a resinous adhesive is utilized for rolling the tube, a suitable wax such as paraffin is included in the adhesive. A subsequent wax impregnation step is then not required. Other waxes such as ceresin or microcrystalline waxes derived from petroleum waxes can be substituted for paraffin wax in either the adhesive or the wax impregnation step, if desired. Evanescent end closures such as those formed from the tubular body or a breakable top wad can be utilized in crimping the loaded cartridge and other known sequence of steps can be followed in preparing the laminated tubular body, if desired. It is particularly advantageous to fold the tube about the outer edge of the basewad and to press it snugly against the surface of the wad at the bend substantially as illustrated in the drawing because such a construction results in optimum strength and prevents the plastic head from becoming severed from the tube when the shell is fired.

It is to be noted, that by properly controlling the dimensions of conical pin 8 provision can be made for casting a plastic tube 21 between pin 8 and the wall of cylindrical channel 24 through basewad 7. This tapering plastic tube 21 is smaller in diameter than the external diameter of battery cup 13 and is expanded thereby upon its insertion therein and assists in securing the primer assembly within the head. It has also been found that the function of pin 8 when acting as a guide pin to properly position the tubular body assembly in cavity 5 is an important one as the good extracting properties of the cartridge having a plastic head are at least partially due to the exact alignment of the tubular body with the head as is made possible by this invention. This alignment can be accomplished much more accurately than is possible when assembling a metallic head with a tubular body. If the tubular body and head of the cartridge are not properly aligned and the axis of the primer assembly not concentric with the axis of the head, the cartridge becomes cocked in the gun chamber and the resulting binding thereof against the chamber walls renders extraction of the fired cartridge case difficult. Pin 8, while preferably nearly conical, can, of course, be made in other suitable shapes such as a truncated cone.

Having described the invention, what is claimed and desired to secure by Letters Patent is:

1. In a gun cartridge, a case comprising an orificed basewad, a laminated paper tubular body compressibly fitted over said wad and having one end thereof embedded at an open angle with said basewad in a set plastic head having a primer pocket, the plastic head comprising a base with an integral extraction rim thereabout, tubular sidewalls integrally projecting from the base about said tubular body and into said open angle, respectively, in the region of the basewad and a smaller substantially cylindrical tube integrally projecting from the base of the head as an extension for the primer pocket from said head into the orifice of said basewad, the smaller tube and primer pocket being concentric with the projecting tubular side walls and extraction rim of the plastic head.

2. The cartridge case of claim 1 wherein the tubular primer pocket tapers from the pocket diameter of the opening in the base of the head to a diameter of less dimensions in the extension and a primer wedged into retention in said pocket.

3. A loaded gun cartridge having an orificed basewad, a powder charge, at least one overpowder wad and a projectile charge contained in a case comprising a flexible laminated paper tubular body having one end thereof extending beyond said basewad and folded inwardly until pressed snugly about the outer edge of said basewad to form an angle therewith, said end being retainably embedded in a pressure molded and set plastic head extending into said angle and carrying a primer press-fitted

therein for retention, said case having a crimped closure at the other end of said body.

4. In the manufacture of gun cartridges, the process for making cases therefor which comprises providing a paper tube, placing a compressed orificed basewad within the tube in a position intermediate its ends closer to one end than to the other such that a portion of the tube projects from the bottom end thereof, folding said projecting portion inwardly toward the bottom of said wad around the outer edge thereof to leave said bottom and portion in spaced relationship, and forming a plastic head in situ about the folded projecting portion of the tube embedded therein and at least said bottom of said basewad.

5. A shotshell cartridge case comprising a laminated paper tube, a substantially flat-bottomed centrally orificed basewad compressed within said tube and disposed proximate one end of the tube, that end portion of the tube extending beyond the basewad being bent toward the center of the tube around the outer edge of said wad and forming an acute angle therewith, the bent portion of the tube being retainably embedded in a plastic head provided with a peripheral extension embracing an outer portion of the tube lateral to at least about half of the length of said basewad and with a centrally located extension embracing at least part of the interior surface of the basewad orifice.

6. A method of making a shotshell case comprising providing a laminated paper tube, positioning a substantially flat-bottomed, orificed basewad within said tube intermediate its ends with the bottom of said wad approximate one end of the tube with a portion of the tube projecting beyond said bottom of the basewad, folding the projecting portion of the tube inwardly thus forming a bent portion at an angle greater than 90° and less than 180° between the straight portion of the tube and the said bent portion of the tube, and molding and setting in situ a plastic head about at least half way up that end of the tube containing the basewad with a portion of the plastic head also being molded in the angle remaining between the basewad and the bent projecting portion of the tube.
